UNITED STATES PATENT OFFICE.

HELENE L. SWEENEY, OF BOSTON, MASSACHUSETTS.

PORTIÈRE-HOOK.

1,236,883.

Specification of Letters Patent. Patented Aug. 14, 1917.

Application filed March 14, 1917. Serial No. 154,837.

To all whom it may concern:

Be it known that I, HELENE L. SWEENEY, a citizen of the United States, residing at Boston, county of Suffolk, State of Massachusetts, have invented an Improvement in Portière-Hooks, of which the following description, in connection with the accompanying drawing, is a specification, - like characters on the drawing representing like parts.

This invention relates to a device for application to a portière, curtain or similar article presenting a hook by which the portière, curtain or other article may be suspended from a suitable support such as the usual curtain rings upon a curtain rod.

The invention is in general an improvement upon the portière holder disclosed in my application Serial No. 130,257, filed November 8, 1916 and the main object is to provide for the swiveling of the hook of the type of portière holder disclosed in the said application.

A further object of the invention is to provide for a simple and cheap construction wherein the body of the portière holder is secured together by the same features which secure the swiveling feature of the hook portion.

The invention presents a portière holder which is self-attachable to the portière, curtain or other article and which therefore requires no sewing or fastening to hold it in place, and one in which by reason of the swiveling feature of the hook the portière, curtain or other article automatically adjusts itself with respect to the device from which it is suspended.

The invention as in the case of the portière holder disclosed in my aforesaid application provides a device in which the body or frame of the device is inserted within the upper folded edge of the portière and lies concealed within the fold. It further presents a device with an extended straight upper edge, upon which the fold of the portière rests, and is provided with a pointed hook readily insertible through the material of the portière.

These and other objects and features of the invention will appear more fully from the accompanying description and drawings and will be particularly pointed out in the claims.

The drawings show the invention in its preferred form for supporting a portière

on an ordinary rod provided with curtain rings.

In the drawings,

Figure 1 is a side elevation of a preferred form of portière holder embodying the invention;

Fig. 2 is a top plan view of the construction shown in Fig. 1 with the shank of the hook section in cross section;

Fig. 3 is a perspective showing a curtain rod, rings and portière suspended therefrom by the aid of the device embodying this invention.

The device as shown by Figs. 1 and 2 of the drawings is formed entirely from wire which should be of sufficient size and strength to enable the device to maintain its shape under ordinary conditions of use and yet be of sufficient flexibility to enable it to be bent into the required shape.

The device comprises two portions, namely, the body portion and the hook portion.

The body portion is a thin flat frame with an extended upper straight edge adapted to lie within the folded edge of the portière and to support the portière upon the straight upper edge portion. This body portion is formed preferably of a suitable piece of wire bent to form the straight upper edge portion 1 with both ends bent back from said straight portion in the same plane and overlapped preferably at the center.

The hook portion comprises a shank 2 and the fabric penetrating curved point 3. The hook portion is journaled vertically in the body to present an upstanding hook and by being journaled in the body is thus swiveled so that the hook may turn at any desired angle with respect to the body portion.

The shank of the hook is journaled in vertically alined holes formed in the upper and lower portions of the body. For this purpose the central portion of the straight upper portion of the body is flattened at 4 and the overlapping ends are flattened at 5 and 6 and the vertically alined holes are formed in these flattened portions.

Preferably also the shank of the hook is flattened at 7 between the portions of the frame of body and is also headed at 8 at its lower end. The hook thus serves to secure together the overlapped ends of the body portion and is itself held in proper relation with respect to the body portion by the flattened portion 7 and the head 8.

The point of the hook 3 is bent slightly

outward as shown and is sharpened to a dull point so that it may readily penetrate the goods upon which the article to be supported is formed without tearing or injuring the same.

The portion upstanding above the body portion is preferably of just sufficient size to pass through and project above the folded edge 9 of the portière or curtain 10. It is thus inconspicuous and yet of ample size and strength to enable it to be hooked in, and thus secured to, the usual rings 11 running on the rod 12.

The device issued in the same manner as the device disclosed in my aforesaid application. When the portière 10 has one end 13 folded over, the hook 3 is inserted from the inside through the folded edge 9 and drawn through until the extended upper straight portion of the body 1 lies against the inside of the folded edge while the thin flat frame of the body portion lies flat between the two layers of the portière. Thus the entire body portion of the device is concealed from view and the hook alone projects above the curtain edge. The swiveling feature of the hook with respect to the body portion enables the portière to assume any position and to be easily pushed back into folds. It is unnecessary to attach the device by sewing or otherwise to the portière. As many of the devices are used as are necessary and as are required by the article to be supported. The folded portion 13 of the portière may be as narrow as desired and may be sewed to the main layer of the portière in the usual manner.

It will thus be seen that a construction is presented which is readily manufactured, which is of a minimum cost, but which is of ample size and strength to perform its function while being inconspicuous or practically invisible.

Having fully described my invention, what I claim as new and desire to secure by Letters Patent is:

1. A portière holder formed from wire and comprising a thin flat body member to lie within the folded edge of the portière, presenting an extended straight upper portière supporting portion with both ends bent back from said straight portion in the same plane and overlapped at the center; an upstanding fabric penetrating hook adapted to project above the folded edge and having its shank journaled in vertically aligned holes in the center of said straight portion and in said overlapped ends, whereby the hook is swiveled to the body and the overlapped ends are secured together. 50

2. A portière holder having the features defined in claim 1 and having the center of the straight portion and the overlapped ends, in which the aligned holes are located, flattened transversely. 65

3. A portière holder having the features defined in claim 1 and having that portion of the hook shank between said aligned holes enlarged and having the lower end of the hook shank headed. 70

In testimony whereof I have signed my name to this specification.

HELENE L. SWEENEY.
